GARMENT PRESSING MACHINE

Thomas Yosyk, Ridgewood, N. Y.

Application August 2, 1935, Serial No. 34,438

2 Claims. (Cl. 38—36)

My present invention relates to garment pressing machines, and particularly to improvements in manually operable pressing machines, wherein the pressing elements are brought to closed position by means of toggle mechanism actuated by a foot lever.

The objects of the present invention include the provision of toggle mechanism for moving the pressing elements to closed and open position, and characterized by ease and evenness of motion both during closing and opening of the press, and providing for relatively small effort against slight amount of movement of the pedal lever when closing the press to obtain a very great pressure between the elements.

The foregoing and all of the objects and advantages of the invention will become more apparent and will be pointed out during the course of the following detailed description of the accompanying drawings, in which

Fig. 1 is a side view partly in section taken on the line 1—1 of Fig. 4, and showing a pressing machine embodying my present invention in closed position;

Fig. 2 is a perspective view of the toggle mechanism of Fig. 1 with parts thereof shown fragmentarily;

Fig. 3 is a view similar to Fig. 1 showing the parts in open position;

Fig. 4 is a view taken on the line 4—4 of Fig. 1; and

Figs. 5, 6 and 7 are diagrammatic views of modifications of the invention.

Referring to Figs. 1—4, wherein is shown a preferred form of the invention, the letter B designates generally a buck or lower pressing element mounted above the usual table T supported on the frame F of the machine. The frame F has at its top an extension 8 on which the head lever 9 is fulcrumed at 10, the lever 9 carrying at its outer end the usual head or upper pressing element H. The rear end of the lever 9 is connected by mechanism designated generally by the numeral 11 (shown and described in detail in my Patent 1,992,342, February 26, 1935) to the upper link 12 of the rear or main toggle which includes also the relatively long lower links 13 pivotally connected at 14 to the link 12 and fulcrumed at 15 on the lower rear portion of the frame F.

The front 16 of the frame F is provided with rearwardly extending wings or brackets 17, to which are secured studs 18 receiving the forward ends of coil springs 19, the rear ends of which are secured to studs 20 on the links 13, the

springs tending to normally break the toggle 12—13 and hold the press in open position.

A shaft 21 is secured between the brackets or wings 17 and forms a journal for the end 22 of the foot lever 23, the other end of which extends through an opening 24 in the front 16 of the frame, and is provided with a pedal 25. A link 26 is pivotally secured at its lower end as designated at 27 to the foot lever 23, and at its upper end is pivotally secured as at 28 to one arm 29 of a bell crank, pivotally mounted on a shaft 30 secured between the brackets 17. The other arm 31 of the bell crank is pivotally connected as at 32 to the forward end of a link 33, the other end of which receives a pin 34 which forms the connection between the links 35 and 36 of a second toggle. The links 35 are pivotally connected at 37 to the long link 13 of the rear main toggle and are provided with an extension 38 projecting beyond the link 13 and having slots 39 to receive the bolts 40, which extend through weight 41 and receive nuts 42 to adjustably hold the weight on the extensions 38.

As stated, the parts described are normally in the position of Fig. 3, at which time the press is open. When the lever 23 is depressed, the parts are moved to the position of Fig. 1, that is, in closed position, and in which position the press may be locked by throwing the toggle 35—36 past dead center. The link 36 is preferably provided with an extension 43, through which is mounted set screws 44, the inner ends of which carry pads 45, to abut the links 35. Obviously, adjustment of the screws 44 will move the pads relatively to the link 35 and thereby provide for locking the machine when it is closed or bringing the parts to closed position without locking it in such position. Where the toggle 35—36 is locked or brought past dead center when the machine is closed, it is desirable to provide means for breaking the toggle to effect opening of the machine, and in this connection I may provide a kick-off lever 46 pivotally mounted at 47 adjacent the pedal lever and provided at its outer end with a treadle 48 and at its inner end with a curved portion 49 engageable with the pedal lever 23 when the treadle 48 is depressed to break the toggle and open the press.

The foregoing description is general, and I wish to call particular attention to the fact that the pedal lever 23 is substantially L-shape having the short arm or end 22 intermediate the pivots 21 and 27, while the remaining portion of the pedal lever constitutes a relatively long arm. By forming the pedal lever as shown, and pivot-

- ally connecting it adjacent the front of the machine, instead of adjacent the rear, I provide a relatively short arm between the fulcrum and the point where the power is applied, and a long arm 5 between the point where the power is applied and the point at which the effort is applied. This not only contributes materially to the ease of movement, but also provides for relatively short movement and slight effort in closing the press.
- 10 Furthermore, by providing the weight 41 on the extension 38 of the link 35, to swing downwardly when the pedal lever is pressed downwardly and the toggle 35—36 is being straightened, I further contribute to the ease of movement and slight 15 effort in closing the press with great pressure at finally closed position. Still a further contribution to the accomplishment of this movement and relatively great pressure is the provision of the plurality of independent connections between 20 the pedal lever and the toggle 35—36, namely, the link 26 which makes a direct pull down on the bell crank arm 29 when the pedal lever is depressed to swing the bell crank on its pivot 33 and turning arm 31 to pull up on link 33 at the 25 point of connection between the links 35—36. The provision of the weight 41 while assisting materially to the accomplishment of the objects of the invention above stated is not absolutely 30 essential and the same may be omitted if desired, and, furthermore, when provided may be adjustable on the extension 38 to desired positions.

While the operation of the parts should be obvious from the foregoing, I will briefly describe 35 the same referring first to Fig. 3, wherein the spring 19 is maintaining the press in open position with the toggles broken and with the pedal lever 23 raised. When the operator steps on the pedal 25 and depresses the same to rock lever 23 on fulcrum 21, the link 26 moves from the vertical position of Fig. 3 to the inclined position of Fig. 1 swinging the bell crank to pull up on link 33 and on pivot 34 straightening toggle 35—36. Simultaneously the weight 41 is lowered assisting 40 in the straightening of the said toggle and further assisting in the straightening of the toggle 12—13, which exerts an upward thrust on the connection 11 swinging the lever 9 on its pivot 10 and closing the head H against the buck B. The connection 11, as explained in my 45 said patent assists in the application of the pressure and automatically adjusts the head H relative to the buck B regardless of the thickness of the material therebetween.

50 In the embodiment of the invention above described in connection with Figs. 1-4, the bell crank is mounted to pull up the toggle 35—36 in closing the press, since the toggle breaks downwardly when the press opens.

55 In Figs. 5, 6, and 7 I have shown modifications of the invention with the movable parts shown in dotted lines at open position of the press and in full lines at closed position of the press.

In Fig. 5, I have shown a modification, where- 60 in the pedal lever 23' is fulcrumed at 21' on shaft or pin extending between the brackets 17' carried by the front of the frame. The L-shaped lever 23' is reversed, that is, the arm which is connected to the shaft 21' is substantially straight 65 and the bend occurs adjacent the pedal 23'. However, as in the embodiment of the invention 70 previously described, the toggle 36—35 is substantially the same and the link 36 is pivotally mounted on the shaft 21' on which the pedal lever 23' is fulcrumed. Instead of having the

link which connects the pedal lever to the bell crank in a normally vertical position, the same is inclined in both open and closed positions of the press, being connected at 27' to the pedal lever and at 28' to the arm 29' of the bell crank. 5 The bell crank is mounted on a pivot 39' on the base of the frame instead of being fulcrumed on the brackets carried by the front of the frame as in Fig. 1. The arm 31' of the bell crank is connected at 32' to the link 33', corresponding to the 10 link 33 of Figs. 1-4, and which link is pivoted on the pin or shaft which serves as the pivotal connection between links 35 and 36, of the toggle 35—36.

In the embodiment of Fig. 5, I obtain the same 15 result, as in the structure of Figs. 1-4, due to the fact that the pedal lever 23' is relatively short, is fulcrumed adjacent the front of the frame, and through the plurality of independent connections, namely, link 26, bell crank lever and 20 link 33' operates the toggle 35—36 which also carries the weight 41' corresponding to the weight 41, and which during closing movement of the press descends to assist in applying the pressure while closing the press. The main difference 25 between the embodiment of the invention in Figs. 1-4, and that of Fig. 6, is that instead of pulling from the pedal lever on one arm of the bell crank, and pushing from the other arm of the bell crank to straighten the toggle 35—36 in closing the press, the link 33' corresponding to the link 33, and the action of the bell crank and parts operated thereby is reversed so that a pushing 30 action is obtained from the pedal lever on one arm of the bell crank to cause the other arm 35 to pull to straighten the said toggle and close the press.

Under this arrangement, that is, the construction of Fig. 5, wherein the toggle 35—36 flexes upwardly, the link 33' corresponding to the link 33 is connected on the shaft 34' at one end and at 32' to the arm 29' of the bell crank, which is mounted on the shaft 30' secured between the wings or brackets 17' on the front wall of the frame similarly to the shaft 30. The arm 31' of the bell crank is pivotally connected to the link 26' also connected at 27' to the foot lever 23'. In the embodiment of the invention being described, the foot lever 23' is substantially the same in construction as the foot lever 23 of Fig. 1, 50 and the location of the fulcrum 21' and the pivotal connection 27' are substantially the same as the arrangement of the fulcrum 21 and connection 27 of Fig. 1.

One difference between the construction and 55 arrangement of parts of Fig. 6, and that of Figs. 1-4, is that the position of the bell crank is reversed, that is, its apex is pointed upwardly with the arms 29' and 31' depending downwardly, whereas in the construction of Figs. 1-4, the arms 60 of the bell crank normally point upwardly and the apex points downwardly. The reason for this is that the toggle 35—36 in Fig. 6, flexes upwardly, so that when the foot lever 23' is depressed, the link 26' pulls down on the arm 31' 65 causing the arm 29' and link 33' to push downwardly to straighten the toggle 35—36, it being understood that during closing of the press, the bell crank in Fig. 6 moves in contra-clockwise direction, and during opening of the press moves 70 clockwise. Since the outer end of the link 35 moves upwardly during the closing of the press, under the construction of Fig. 6, I preferably omit the weight shown on the extensions 38 of Fig. 1, because the weight would have to be lifted 75

during closing of the press, whereas in the construction of Fig. 1 the weight is lowered during closing of the press.

Referring to Fig. 7 it will be noted that the bell crank is mounted similarly to that of Fig. 5, but the link 26''' is connected to the forward arm 31''' of the bell crank instead of to the rear arm as in Fig. 5. This is due to the fact that the toggle 35—36 in Fig. 7 flexes upwardly as in Fig. 6, and it is necessary for the arm 29''' of the bell crank to exert a pull on the link 33''' instead of a thrust as in Fig. 5. The pedal lever 23''' is of slightly different formation than the pedal levers of Figs. 5 and 6, being substantially L-shaped, and yet, including the pedal, being also substantially S-shaped. The link 26''' is connected at 27''' to the pedal lever 23''' intermediate its ends. The bell crank and pedal lever are pivoted on journals 21''' and 30''', respectively, secured between the wings or brackets 17''' on the front of the frame. Obviously, when the pedal lever 23''' is moved from the dotted line position to the full line position, the link 26''' exerts a thrust against, or pushes, the arm 31''' of the bell crank, causing the arm 29''' to pull down on the link 33''' to straighten the toggles and close the press.

I claim:

1. In a pressing machine including a frame, a pair of pressing elements one movable relatively to the other, a main toggle consisting of two interjointed links, one of which links is connected to said one element and the other of which links is fulcrumed on said frame, a second toggle consisting of interjointed links having one link connected to one of the links of the first toggle device and the other link fulcrumed on the frame, a bell crank lever pivotally mounted on the frame adjacent to the front thereof, a link operatively connecting one arm of said bell crank and the jointed ends between the two links of the second toggle device, a pedal lever pivotally mounted on

the frame jointly with the mounting of the end of one of the links of the second toggle device for relatively short movement, and a link connecting said pedal lever and the other arm of the bell crank device, so that actuation of the pedal lever ⁵ will cause a straightening out of the toggle devices so as to bring the pressing elements into pressing relation.

2. In a pressing machine including a frame, a pair of pressing elements one movable relatively to the other, a main toggle device consisting of two interjointed links having one link connected to said one element and the other link fulcrumed on said frame, a second toggle device consisting of interjointed links having one link connected ¹⁰ to one of the links of the first toggle device and the second link fulcrumed on the frame, a bell crank lever pivotally mounted on the frame adjacent to the front portion thereof, a link operatively connecting one arm of said bell crank ¹⁵ lever and the jointed connection between the ends of the two links of the second toggle device, a pedal lever pivotally mounted in the frame adjacent to the front portion thereof, the pivotal mounting being at the same point where one of ²⁰ the links of the second toggle device is pivoted to the front portion of the frame, a link operatively connecting said pedal lever at a point below where the end thereof is pivoted to the frame with the other arm of said bell crank lever, ²⁵ so that upon depression of the said pedal lever the toggle devices will all jointly operate for the purpose of bringing the pressing elements into pressing relation, the link which connects the pedal lever and the bell crank lever exerting a ³⁰ pull on the bell crank lever, and the link which connects the bell crank lever with the joint between the links of the second toggle device exerting a pull on said second toggle device. ³⁵
